FIG. 3

UNITED STATES PATENT OFFICE

WILFORD G. BARTENFELD, OF LORAIN, OHIO

CHANNEL CONSTRUCTION FOR BULKHEADS

Application filed March 27, 1929. Serial No. 350,240.

This invention relates to channel construction for bulk heads, and has for its main object to provide a bulk head which is constructed of standard steel channels to eliminate the use of the usual transverse stiffeners.

Another object of the invention is to provide a bulk head constructed of standard steel channels arranged vertically in staggered sets with their flanges extending inwardly and transverse plates arranged between said sets.

A further object of the invention is to provide a bulk head of the above character, the construction of which is easily adapted to various rigidity as required by using suitable widths of said transverse plates.

With the above and other objects in view, the invention will be hereinafter fully described as illustrated in the accompanying drawings, and the novel features thereof will be particularly pointed out in the appended claims.

In the several views of the drawings, similar characters of reference are used to indicate corresponding parts.

Figure 1 illustrates in elevation a bulk head constructed in accordance with my invention,

Fig. 2 is a cross sectional view taken on line 2—2 of Fig. 1,

Fig. 3 is a similar view to Fig. 2 on an enlarged scale,

Fig. 4 is a cross sectional elevation, on an enlarged scale, taken on line 4—4 of Fig. 1,

Fig. 5 is a cross sectional elevation, on an enlarged scale, taken on line 5—5 of Fig. 1,

Fig. 6 is a similar view to Fig. 5 illustrating the filling of concrete,

Fig. 7 is a longitudinal sectional elevation of a fragmental portion of the upper portion of the bulk head illustrating the means of connecting the transverse plates thereof to the deck of the vessel,

Fig. 8 illustrates in elevation, a modification of the construction for bulk heads, and

Fig. 9 is a sectional plan view of Fig. 8.

Referring to the drawings, 1 represents the outer shell or side tank of a vessel, 2 the tank top and 3 the deck thereof, to which is fixed the bulk head now to be described. This

bulk head is constructed of standard steel channels 4 and 5, which are arranged vertically in sets in spaced and staggered relation with their flanges indicated by 6 extending inwardly and connected together by rivets as at 7. Plates indicated by 8 are arranged between the sets of channels, and the flanges of the end channels are connected to said plates by rivets 9. The vertical and transverse plates 8 may be of any suitable width to give the desired rigidity to the bulk head. The free side flanges of the end sets of channels indicated by 10 are cut off at 11 to allow for slight variations in the width of the channels and the distance between the outer shells or side tanks of the vessel to which the bulk head is to be connected. An angle bar 12 is riveted to the channel 10 and said angle bar to the outer shell or side tank 1.

The channels 4 and 5 are of equal length, 70 their upper ends and also their lower ends being in alignment. The lower ends of the channels 4 are riveted, as indicated at 13, to a plate 14, which is cut at its lower edge 15 to conform to the camber of the tank top 2, 75 to which it is connected by means of an angle bar 16. A vertical angle clip 17 connects the end of the plate 14 to the outer shell 1 of the vessel. The lower ends of the channels 5 are similarly connected to the tank top by 80 a plate 18 and an angle bar 19. The plates 14 and 18 have upper inturned flanges 20 and 21 extending between the sets of channels for strengthening said plates. Angle clips 22 are employed to connect the lower ends 85 of the transverse and vertical plates 8 to the tank top 2. The alternating recesses or pockets 23 and 24 formed by the sets of channels 4—5 and the vertical plates 8 and the longitudinal plates 14—18 are preferably 90 filled with concrete indicated by 25 which slopes as shown at 26 to insure coal, grain and similar cargoes sliding therefrom.

The upper ends of the channels 4 and 5 are riveted as indicated at 27 to longitudinal 95 plates 28 and 29, which are cut at their upper edges 30 to conform to the camber of the deck 3 of the vessel, and said plates are fixed thereto by longitudinal angle bars 31 and 32. A vertical angle clip 33 connects 100

each end of the longitudinal plate 28 to the outer shell of the vessel. Angle clips 34 connect the upper ends of the transverse and vertical plates 8 to the deck 3.

In the modification, Figs. 8 and 9, the vertical channels 35 and 36 are connected to short longitudinal plates 37 and 38 instead of the longitudinal plates 14 and 18, and short longitudinal angle bars 39 and 40 connect said plates to the tank top. By this construction the alternating pockets 23 and 24 of the first described construction are entirely open at their rear and forward sides. Similar short plates and angle bars connect the upper ends of the channels 35 and 36 to the deck of the vessel.

From the drawings and description, it will be seen that a bulk head thus constructed of standard steel channels and transverse plates is rigid due to the flanges of the channels serving as stiffening means without the use of transverse stiffeners, that this construction permits varying the rigidity of the bulk head by employing greater or less widths of transverse plates, and that this bulk head is readily fitted between and connected to the outer shells or side tanks, to the tank top, and to the deck of the vessel.

Although the construction set forth is for a transverse bulk head and is well adapted to accomplish the intended purposes, it will be understood that said construction may apply to a longitudinal bulk head, and that slight changes in the details of construction may be made within the scope of the claims.

Having fully described my invention, what I claim is:

1. In a construction for bulk heads, the combination of channels, the channels being arranged in sets, the sets being arranged in transverse spaced relation, the flanges of the sets of channels extending inwardly, plates, the sets of channels being connected to said plates, plates cut to the camber of the tank top, plates cut to the camber of the deck, said cambered plates being connected to said channels, and said plates cut to the camber of the tank top having inwardly extending flanges between the first mentioned plates.

2. In a construction for bulk heads, the combination of channels, the channels being arranged in sets, the sets being arranged in transverse spaced relation, the flanges of the sets of channels extending inwardly, plates, the sets of channels being connected to said plates, plates cut to the camber of the tank top, plates cut to the camber of the deck, said cambered plates being connected to said channels, said plates cut to the camber of the tank top having inwardly extending flanges between the first mentioned plates, the space between the first mentioned plates and said flanged portion of said plates being filled with concrete, and the concrete having a sloping top.

3. In a construction for bulk heads, the combination of channels, the channels being arranged vertically in sets, the channels of each set being connected together at their flanges, the sets of channels being arranged in transversely spaced and staggered relation, the flanges of the channels extending inwardly, plates, the plates being vertical, and the end flanges of said sets of channels being connected to said vertical plates. 75

4. In a construction for bulk heads, the combination of channels, the channels being arranged vertically in sets, the channels of each set being connected together at their flanges, the sets of channels being arranged in transversely spaced and staggered relation, the flanges of the channels extending inwardly, plates, the plates being vertical and connected to the end flanges of said sets of channels, plates cut to the camber of the tank top, plates cut to the camber of the deck, and said cambered plates being connected to said sets of channels. 80

5. In a construction for bulk heads, the combination of channels, the channels being arranged vertically in sets, the channels of each set being connected together at their flanges, the sets of channels being arranged in transversely spaced and staggered relation, the flanges of the channels extending inwardly, plates, the plates being vertical and connected to the end flanges of said sets of channels, plates cut to the camber of the tank top, plates cut to the camber of the deck, and said cambered plates being connected to said sets of channels. 85

6. In a construction for bulk heads, the combination of channels, the channels being arranged vertically in sets, the channels of each set being connected together at their flanges, the sets of channels being arranged in transversely spaced and staggered relation, the flanges of the channels extending inwardly, plates, the plates being vertical and connected to the end flanges of said sets of channels, plates cut to the camber of the tank top, plates cut to the camber of the deck, said cambered plates being connected to said sets of channels, and angle bars connected to said cambered plates. 100

7. In a construction for bulk heads, the combination of vertical channels, the flanges of the channels extending longitudinally relative to the vessel, the channels being arranged in transverse spaced relation relative to the vessel, vertical plates, and the channels being connected to said plates. 115

8. In a construction for bulk heads, the combination of channels, the flanges of the channels extending longitudinally relative to the vessel, the channels being arranged in transverse spaced relation relative to the vessel. 120

sel, the channels being staggered, plates, and the channels being connected to said plates.

9. In a construction for bulk heads, the combination of vertical channels, the flanges of the channels extending longitudinally relative to the vessel, the channels being arranged in sets, the sets being arranged in transverse spaced relation relative to the vessel, the flanges of the sets of channels extending inwardly, vertical plates, the plates extending longitudinally relative to the vessel, and the end flanges of said sets of channels being connected to said plates.

10. In a construction for bulk heads, the combination of channels, the channels being arranged vertically and in transverse spaced relation relative to the vessel, the flanges of the channels extending longitudinally relative to the vessel, plates, the channels being connected to the plates, plates cut to the camber of the tank top, plates cut to the camber of the deck, and said cambered plates being connected to said channels.

In testimony whereof I affix my signature.

25 WILFORD G. BARTENFELD.
